NO. 14,543

JAN 8, 1884

UNITED STATES PATENT OFFICE.

ISAAC NEWTON POE, OF TOLEDO, OHIO.

DESIGN FOR A SEWING-MACHINE STAND.

SPECIFICATION forming part of Design No. 14,543, dated January 8, 1884.

Application filed October 4, 1883. Term of patent 7 years.

To all whom it may concern:

Be it known that I, ISAAC N. POE, a citizen of the United States, resident at Toledo, in the county of Lucas and State of Ohio, have invented a certain new and ornamental 5 Design for Sewing-Machine Stands, for which I desire Letters Patent for a term of seven years; and I do declare the following to be a full, clear, and exact description of the invention, such as will enable others skilled in the art to which it appertains to make and use the same, reference being had to the accompanying drawing and to letters or figures of reference marked thereon, which form 10 a part of this specification.

The figure of the drawing is a representation of a perspective view of the ornamental design for sewing-machine stands.

This design relates to sewing-machine stands. The frame has a rectangular open-

ing between the end pieces. Ornamental drawers having ring-knobs are placed on brackets at the ends of the framing beneath a table having a molded edge. Upon the table is a cover having a top in imitation of a 25 Mansard roof and a molded base surrounding it.

I claim—

The design for a sewing-machine stand, consisting of the frame, having the rectangular 30 opening between its end pieces, the brackets and drawers having ring-knobs, and the cover in the form of a Mansard roof with a molded base surrounding it, as shown and described.

In testimony whereof I affix my signature in 35 presence of two witnesses.

ISAAC NEWTON POE.
